UNITED STATES PATENT OFFICE.

CHARLES L. GOODRUM, OF NEW YORK, N. Y., ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,215,925.

Specification of Letters Patent. Patented Feb. 13, 1917.

Application filed August 23, 1915. Serial No. 46,891.

To all whom it may concern:

Be it known that I, CHARLES LANE GOODRUM, a citizen of the United States, residing at New York, in the county of New York 5 and State of New York, have invented certain new and useful Improvements in Telephone-Exchange Systems, of which the following is a full, clear, concise, and exact description.

10 This invention relates to telephone exchange systems, and more particularly to circuit arrangements for selector switches employed in automatic or semi-automatic telephone exchanges.

15 It is the object of this invention to provide a new and useful circuit arrangement for a final selector or connector switch.

According to this invention, upon the completion of the connection, the called line 20 is supplied with current through the winding of a relay used also for the testing of the desired line. Thus the test relay controlling the operation of the selector switch serves a double purpose, the necessity of providing 25 special resistances through which current may be supplied to the called line being done away with.

The drawings represent diagrammatically 30 an automatic telephone exchange system, and more in detail the circuits of a final selector or connector switch, only so much being shown of the apparatus and the circuits as is necessary for a clear understanding of the invention.

35 The subscriber at substation 1 desiring to establish a connection with a substation 2, removes his receiver from the switchhook and operates a calling device 3 for extending his line by means of switching mechanism 40 comprising a selector switch 4 to an incoming line or trunk leading to a selector switch 5. A circuit is closed from grounded battery through the left-hand winding of a line relay 6, the calling incoming line circuit and 45 the right-hand winding of relay 6, to ground. Relay 6 by attracting its armature closes an energizing circuit for a slow-acting relay 7.

The subscriber at substation 1 proceeds 50 now to send out the tens and units impulses for controlling the setting of the final selector or connector. By operating the calling

device 3, the subscriber produces short interruptions in the incoming line circuit for intermittently deenergizing and energizing relay 6. In response to the first deenergization of relay 6 a circuit is closed from grounded battery through the winding of primary magnet 8, a wiper 9 of a side switch associated with connector 5, conductor 10, 60 the right-hand front contact and armature of the relay 7, and the back contact and armature of relay 6, to ground. A further circuit is closed from ground through the armature and back contact of relay 6, the 65 right-hand armature and front contact of relay 7, and the winding of a slow-acting relay 11, to grounded battery.

In response to each deenergization of relay 6, magnet 8 receives an impulse and 70 causes the stepping of the connector brushes in a rotary direction to select a group of outgoing lines in which the line leading to the called substation 2 is located. Relays 7 and 11 being slow to release, remain energized during the vibration of the armature of relay 6. Upon the energization of relay 11, a circuit is closed from grounded battery, through the winding of slow-acting escapement magnet 12, conductor 13, the right- 80 hand armature and front contact of relay 11, the left-hand armature and front contact of relay 7, conductor 14, and the armature and back contact of a slow-acting ringing relay 15, to ground. Escapement magnet 12 becomes energized and is maintained actuated 85 during the sending out of a series of impulses.

After the tens impulses are sent out, a longer interruption is produced in the incoming line circuit and relay 6 remains deenergized for a sufficient period to permit the deenergization of slow-acting relay 11, whereupon the circuit of magnet 12 is opened. This magnet becomes deenergized 90 and allows the side-switch wipers to escape into position 2. In this position of the side-switch, primary magnet 8 is disconnected and the secondary magnet 16 is connected in circuit. 95

The subscriber at substation 1 proceeds 100 now to send out the units impulses. Relay 11 and magnet 12 become energized in the same manner as above described, but the im-

pulses repeated by relay 6 are transmitted to a secondary magnet 16 instead of the primary magnet 8. Under the control of magnet 16 the brushes of connector 5 are stepped 5 in a vertical direction onto the line leading to the called substation 2. After the sending out of the units impulses, relay 6 retains its armature attracted and opens the circuit of relay 11. Relay 11 slowly releases and 10 opens the circuit of magnet 12.

As well known, the busy or idle condition 15 of the substation lines is designated by certain electrical conditions existing on the multiple test terminals thereof. Let us suppose that in the present case the busy condition 20 of substation 2 is indicated by a ground connection to test terminal 20 and the multiples thereof, and the idle condition of this substation by a grounded battery connection to this terminal.

As soon as the test brush 21 reaches terminal 20 individual to the called station, and if this station is not engaged in conversation as a calling or called subscriber, a 25 circuit is established from grounded battery through terminal 20, brush 21, side-switch wiper 22, conductor 23, left-hand back contact and armature of relay 11, conductor 24, contact 25 of a test relay 26, side-switch 30 wiper 27, and the left-hand winding of relay 26, to battery. This circuit is closed after the opening of the circuit of the slow-acting escapement magnet 12. The called line being idle, relay 26 does not become energized and therefore the circuit of magnet 35 12 is opened upon the retraction of the armature of relay 11. Magnet 12 becomes energized and moves the side-switch wipers into position 3.

In position 3 of the side-switch, a circuit 40 is closed from grounded battery through the winding of magnet 12, conductor 13, side-switch wiper 30, conductor 31, the left-hand front contact and armature of relay 7, conductor 14, the armature and back contact of relay 15, to ground. Upon the energization 45 of magnet 12 a ringing circuit is established from ground through a ringing current generator 32, the front contact and armature of magnet 12, side-switch wiper 33, the called 50 substation loop and side-switch wiper 34, to ground, for signaling the called station. As soon as the called subscriber at station 2 removes his receiver from the switchhook, relay 55 15 becomes energized and opens the circuit of escapement magnet 12, whereupon the side-switch wipers are moved into position 4. Relay 15 becomes deenergized and the ringing current is disconnected from the 60 called line. A circuit is also closed from ground through side-switch wiper 35, the right-hand winding of relay 26, the called substation loop, side-switch wipers 33 and 27 and the left-hand winding of relay 26, to

grounded battery for energizing this relay. 65 The called substation is supplied with current through the windings of test relay 26, and the calling station through the windings of relay 6.

In positions 3 and 4 of the side-switch, a 70 ground is connected through side-switch wiper 22 to terminal 20 and the multiples thereof for making the selected lines inaccessible to other incoming calls.

Upon the termination of the conversation, 75 the calling and called subscribers restore their receivers, opening thereby the circuits of relays 6 and 26. Relay 7 becomes deenergized and a circuit is closed from grounded battery, through the secondary winding of 80 an induction coil 40, the winding of a restoring magnet 41, the right-hand armature and back contact of relay 26, an off-normal contact 42 of connector 5, conductor 24, the left-hand back contact and armature of relay 7, conductor 14, the left-hand armature and back contact of relay 15, to ground. This circuit remains closed as long as contact 42 is closed, *i. e.*, until connector 5 returns to its normal position, magnet 41 causing 85 the restoration of the side-switch and connector 5 to normal.

If the called line is busy, *i. e.* if ground 90 is connected to terminal 20, the above traced circuit of relay 26 results in the energization of this relay. Relay 26 closes a circuit from ground through the back contact and armature of relay 15, conductor 14, the left-hand armature and front contact of relay 7, conductor 31, the left-hand armature and front contact of relay 26, conductor 50, side-switch wiper 30 and the winding of escape magnet 12, to grounded battery. The escape magnet is maintained energized after the deenergization of relay 11 and the side-switch wipers remain in position 2. A circuit is closed from grounded battery through the secondary winding of inductance coil 40 100 the winding of magnet 41, the right-hand armature and front contact of relay 26, side-switch wiper 35, the right-hand winding of relay 26 and the calling substation loop. A characteristic signal is sent to the calling substation from an alternating current source 51 for indicating the busy condition 115 of the desired line.

The calling subscriber restores his receiver to the switchhook opening thereby the incoming line circuit. Relays 6 and 7 120 and magnet 12 become deenergized, and the side-switch wipers are moved into position 3. In this position, relay 26 is deprived of current and a circuit is closed from grounded battery through the primary winding of induction coil 40, the winding of magnet 41, the right-hand armature and back contact of relay 26, off-normal contact 42, the left-hand armature and back contact of relay 7, 125

conductor 14, and the armature and back contact of relay 15, to ground. Magnet 41 becomes energized and causes the restoration of the side-switch wipers and the connector 5. 5 Selector 4 and the other apparatus employed in the building up of the connection are restored to normal in any well-known manner.

What is claimed is:

- 10 1. In a telephone exchange system, a plurality of lines, a selector switch for extending a calling to a called line, a relay associated with said selector for testing the busy or idle condition of the called line, and means for supplying current for talking purposes to the called line through a winding of said relay.
- 15 2. In a telephone exchange system, a plurality of lines, a selector switch for extending a calling to a called line, a double wound relay for testing the busy or idle condition of a selected called line, and means for supplying current for talking purposes to the called line through the windings of said relay.
- 20 3. In a telephone exchange system, a plurality of lines, a selector switch for establishing a connection between a calling and a called line, a relay for testing the busy or idle condition of the called line, said relay controlling the completion of the connection, and means for supplying current for talking purposes to the called line through the winding of said relay if said line has been found 25 idle.
- 25 4. In a telephone exchange system, a plurality of lines, a selector switch for extending a calling to a called line, a double wound relay for testing the busy or idle condition of the called line, a restoring magnet for said selector switch, means for sending a characteristic signal to the calling line through a winding of said relay if the called line is busy, the operation of said means

and said restoring magnet being controlled 45 by said relay.

5. In a telephone exchange system, a plurality of lines, a selector switch for extending a calling to a called line, a relay adapted to be actuated if the called line is found 50 busy, a restoring magnet for said selector switch, means operative upon the actuation of said relay for sending a characteristic signal to the calling line, and means operative upon the reaction of said relay for closing an actuating circuit for said restoring magnet. 55

6. In a telephone exchange system, a plurality of lines, a selector switch for extending a calling to a called line, a relay adapted 60 to be actuated if the called line is found busy, a restoring magnet for said selector switch, an apparatus for producing a characteristic signal, means operative upon the actuation of said relay for connecting said 65 apparatus through the winding of said restoring magnet to the calling line, means controlled by the calling line for causing the reaction of said relay, and means operative thereupon for disconnecting said signaling 70 apparatus and establishing an actuating circuit for said restoring magnet.

7. In a telephone exchange system, a plurality of lines, a selector switch for establishing a connection between a calling and 75 a called line, a double wound relay for testing the busy or idle condition of the called line, means for sending a characteristic signal to the calling line through one of the windings of said relay if the called line is 80 busy, and means for supplying current for talking purposes to the called line through the other winding of said relay.

In witness whereof, I hereunto subscribe my name this 20th day of August A. D., 85 1915.

CHARLES L. GOODRUM.
